UNITED STATES PATENT OFFICE

RALPH LESLIE RAYMOND, OF MONTREAL, QUEBEC, CANADA, ASSIGNOR TO DOMINION WOOD HEEL CORPORATION, LIMITED, OF MONTREAL, CANADA, A CORPORATION

WOOD-HEEL-TURNING MACHINE

Application filed December 30, 1926. Serial No. 157,999.

The present invention relates to heel turning machines and is illustrated as embodied in a wood heel turning machine of the type disclosed in United States Letters Patent No. 1,488,534, granted April 1, 1924 on the application of Folsom, Vinton & Whitney.

One of the objects of the invention is to provide more accurate means for the adjustment of the upper and lower tracks on which the heel blank holding jack is adapted to ride. For the purpose of supporting the upper track, a pair of brackets are slidably supported by the frame and have the ends of the upper track pivoted between them. In accordance with one feature of the invention, in the illustrated embodiment of the invention, each such bracket carries a rack meshing with the pinion journaled to the frame, and a worm which is also journaled to the frame meshes with the pinion so that the brackets may be adjusted in elevation by this means.

The lower track of the machine is pivoted to a pair of brackets which are also adjustable in elevation on the frame of the machine. In accordance with a second feature of the invention, these brackets are in the form of curved arms parallel to the track for a distance and are fitted at their ends with eccentric cylinders on which the track rests. Thus the lower track may be adjusted roughly by the brackets and by the pivotal connections between the track and the brackets, and finally by the eccentric members on which the track rests. Preferably, also a locking means is provided for holding the eccentric members in their final position so as not to be disturbed by the operation and vibration of the machine.

A further feature of the invention resides in an improved driving mechanism for the cutter shafts. In the machine shown a gear box contains the two cutter shafts and a drive shaft extending from a motor, and means are provided for connecting the three shafts to drive the cutter shafts, whereby two similar units are provided for driving the two cutter heads. The drive shaft and an intermediate shaft which is provided carry interengaging gears which serve merely to connect the

shafts and to support smaller condensite celoron gears which mesh with pinions on the cutter shafts. Thus, the noise which would be caused by the rapid speed of the pinions is greatly reduced by the peculiar composition of the drive gears. The drive shaft is preferably spaced on the right hand side of the machine in order to operate the right hand cutter without intermediate gearing, since his cutter is the first to attack the rough heel blank and is thus subjected to harder usage than the left hand cutter which is driven through the intermediate shaft and gearing.

Still another object of the invention is the provision of novel means for attaching and removing the cutters to and from the cutter shafts. As illustrated, each cutter is held on its shaft by a nut screw on the upper end of the shaft, and the exposed upper extremity of the shaft is squared. Adjacent to each cutter shaft the frame of the machine supports or is formed with a rest. A bent strap is provided for attachment to the rest and also to receive the nut on the shaft and hold it against turning. The nut may be loosened by application of a suitable tool to the squared end of the shaft, and the torque incurred by this turning extends only from the squared end to the adjacent nut rather than through the entire length of the shaft as in the case where the nut itself is removed by a tool and the shaft held from below as has been the practice.

The invention is fully disclosed in the following description and in the accompanying drawings in which:

Figure 1 is a side elevation of the machine;

Figure 2 is a detail of Fig. 1;

Figure 3 is a detail section on the line 3—3 of Figure 2;

Figure 4 is a plan view;

Figure 5 is a detail elevation of Fig. 1;

Figure 6 is a perspective view of one of the straps;

Figure 7 is a detail elevation of Figure 1;

Figure 8 is a front vertical sectional detail;

Figure 9 is a section on the line 9—9 of Figure 8;

Figure 10 is a detail section taken diamet-

rically through the gears from the same view point as that of Figure 8; and

Figure 11 is a detail vertical section as seen from the side.

5 Reference to these views will now be made by use of like characters which are employed to designate corresponding parts throughout.

With reference more particularly to Figure 10 1 the frame of the machine is indicated by the numeral 1 and supports a motor 2 on a vertical axis. The frame also supports a gear box 3 having interior mechanism connected by a shaft 4 to the motor shaft 5 by 15 means of a flexible coupling 6.

At each side of the gear box 3 is slidably mounted one of a pair of brackets 7 each having a knuckle 8 at its upper end. Between the two knuckles is pivoted a curved upper 20 track 9 having its ends formed with graduated discs 10 cooperating with index points 11 inscribed on the knuckles 8 as shown more clearly in Figure 4. By this means the upper track may be adjusted angularly and then 25 secured in position by bolt and nut devices 12 passing through the discs and knuckles.

A pair of alined bearing members 13 and 14 (Figure 1) support a vertical spindle 15 to which is pivoted a link 16. This link is 30 formed at one end with clips 17 supporting a vertical spindle 18 having at its upper end a bracket 19 in which a jack base 20 is horizontally pivoted. The jack comprises a head 21 having a pair of racks 22 slidable and adjustable on opposite sides of the base 20 and having pivoted between them the upper jaw 23 of a heel blank clamp. The head 21 carries a pressure device 24 for the upper jaw 23, and this mechanism as well as the construction of the base 20 and adjustable racks 22 is more fully described and claimed in my co-pending application Serial No. 158,100, filed Dec. 30, 1926. The base 20 carries an operating handle 25 and also a roller 26 which 45 rides on the upper track 9.

Adjacent each bracket 7 a worm 27 is journaled on the frame and meshes with a pinion 28, Fig. 7, which is also rotatably supported by the frame. The pinion meshes with a rack 50 29 carried by the bracket 7, whereby the two brackets and consequently the elevation of the pivot supports of the upper track 9 may be regulated.

It will be seen in Figures 8 to 11 that the 55 power shaft 4 from the motor extends into the gear box 3 and has mounted parallel to it an adjacent intermediate shaft 30 also journaled inside the box. The shafts 4 and 30 support narrow meshed cast iron gears 31 and 32 respectively. The gear 31 has an upward sleeve extension 32' which is surrounded by a smaller gear 33 of condensite celoron secured to the gear 31 by pins 34. The shaft 30 is fitted with a collar 35 having a flange 36 lying 60 65 upon the gear 32. Over this collar and in

engagement with the flange is mounted another condensite celoron gear 37 of the same size as the gear 33 and spaced slightly therefrom as shown in Figure 10. Pins 38 are passed through the gear 37, flange 36 and gear 32 so that all these parts turn with the shaft 30.

The gear box 3 is so arranged that the shafts 4 and 30 lie at equal distances from the ends of the track 9 and somewhat behind the track. Inwardly of the ends of the track, the gear box supports a pair of substantially tubular housings 40 each of which contains a vertical cutter shaft 41 mounted in ball bearings 42 at its ends as shown in Figure 11. This figure also illustrates conventional roller bearings 43 for the upper ends of the shafts 4 and 30. The shaft 4, as shown in Figure 9, is received in ball bearings 44 in the bottom of the box 3. An annular space 45 is provided around the shaft and contains a ring 46 screwed on the shaft for supporting the inner ball race 47. The race is held against upward movement by a collar 48 on the shaft, while the outer race 49 is fitted in a notch 50 cut in the wall of the opening 45 and is held down by the usual plate 51. To the bottom of the box is applied a plug 52 having a short ring 53 which threads into the wall of the space 45. The inner circumference of the plug has a wall 54 of about half inch in thickness built thereon and received between the shafts and the ring 46. A narrow space 55 is maintained between the bottom of the box 3 and the gear 31 and leads to the space 45. This construction provides an effective lubricating system which admits oil through the space 55, retains the oil in the space 45 and prevents it from flowing down the shaft 4 by means of the inner collar 54.

The lower ends of the two shafts 41 lie adjacent the condensite celoron gears 33 and 37 and are fitted with pinions 56 meshing with these gears. Condensite celoron is used for the gears 33 and 37 in order to eliminate the noise which would result from the high speed imparted to the pinions 56. The lower gears 31 and 32 serve merely to transmit motion from the shaft 4 to the shaft 30 and to support the drive gears 33 and 37.

The upper ends of the cutter shafts 41 are exposed outside their housings 40 and there equipped with the cutter blades 57 which are clamped down by nuts 58 screwed on the shafts. The upper extremities of the shafts project beyond the nuts and are squared as indicated by the numeral 59 in Figures 1 and 4.

Adjacent each cutter, the top of the frame is formed with a rest 60 having sockets 61, Fig. 11, in diagonally opposite corners thereof. A duct 62 is formed in the rest and in the frame to lead from the socket to the upper ball bearings 42 of the nearer shaft 41. A system of ducts may further be provided to 125 130

lead from the same socket 61 to the bearings of the other shaft 41 so that oil may be fed to these bearings from a single point.

Beneath the gear box 3 a pair of brackets 64 having each an inwardly curved arm 65 are secured to the frame 1 as shown in Figures 1 and 4. The bracket is held to the frame by a bolt 66 passed through a slot in the bracket so that the latter may be adjusted in elevation. A lower track 67 has its ends pivoted to the arms 65 but near the brackets 64 as also shown in Figure 1. Suitable devices, similar to that shown in Figure 4, may be provided at the pivotal connections 68 of the track 67 for adjusting the angle of the latter.

The lower end of the spindle 18 has fixed thereto a lug 69 on which is formed a boss 70. In the boss is threaded a stem 71 carrying at its lower end a yoke 72 in which is journaled a roller 73 riding on the lower track 67. Another lug 74 projects from the boss 70 and receives a screw 75 which bears on one end of the yoke 72. The upper end of the stem 71 carries a knurled head 76 which is used for adjusting the stem with reference to a scale 77 on the top of the boss 70. After adjustment by this device the screw 75 is turned to prevent upward tilting of the yoke 72, so that the yoke 70 is held in proper position at two spaced points.

It has already been indicated that the position of the track 67 may be set roughly by adjustment of the bracket 64 and by angular movement of the track itself about the pivots 68. For final adjustments the free end of each arm 65 has journaled therein a stem 78 carrying at one end an eccentrically mounted cylinder 79 engaging the lower edge of the track and at the other end a knurled head 80 to be engaged by the fingers of the operator for turning the eccentric 79. A plug 81 is slidably mounted in the end of the arm and is penetrated by the stem 78. The plug has a screw 82 depending therefrom and fitted with an exterior nut 83. After the final adjustment has been made by the eccentric 79, the nut 83 is turned to draw the plug 81 in downward direction. At the same time the inner face of the nut binds firmly against the lower face of the arm and the plug 81 exerts a downward binding action on the stem 78, whereby the latter is locked in the desired position.

For the purpose of changing the cutters 57 there is provided a strap 84 bent twice at right angles and having at one end a pair of elongated sockets 85 adapted to receive the similarly shaped lugs 85' on the top of the rests 60. The other end of the strap has a square hole 86 for snugly receiving the nut 58 which locks the cutter. With the parts so arranged, the squared end 59 of the cutter shaft 41 may be engaged by a suitable tool and turned, whereby the nut 58 is loosened therefrom so that the cutter 57 may readily

be removed or replaced. Thus, when the cutter is to be removed the torque caused by turning the shaft extends only between the squared end 59 and the nut 58 rather than over the whole length of the shaft as in the case where an attempt is made to remove the nut by an ordinary wrench, after blocking the shaft at its lower end, as has been the practice.

Slotted plates 87 are mounted adjacent the cutters and are provided with stems 88 passing through ears 89 on the frame 1. The stems have screws 90 threaded on the ends thereof so that the plates may be adjusted with reference to pointers 91 fixed on the frame. Bolts 92 are passed through the slotted plates into the frame for securing the plates after adjustment. The plates are formed with gages 93 extending beneath the cutters in order to co-operate with a pattern 85 93½ on the spindle 18, see Fig. 1, where only the gage 93 farthest from the observer is shown. On the top of the frame is also mounted a slotted arm 94 carrying a shield 95 for aiding in the disposal of wood chips in a manner already known in the art. A bolt 96 is passed through the arm 94 and into the frame for the purpose of holding the shield in adjusted positions.

While a specific embodiment of the invention has been illustrated and described, it is to be understood that various alterations in the details of construction may be made without departing from the spirit of the invention as indicated by the appended claims.

Having thus fully described the invention, what I claim as new and desire to protect by Letters Patent is:—

1. A wood heel turning machine comprising a frame, a pair of lower brackets slidably mounted thereon, curved arms extending from the brackets, a lower track having its ends pivoted to said brackets, and cylindrical rests eccentrically journaled in the free ends of said arms and supporting said track.

2. A wood heel turning machine comprising a frame, a pair of lower brackets slidably mounted thereon, curved arms extending from the brackets, a lower track having its ends pivoted to said brackets, cylindrical rests eccentrically journaled in the free ends of said arms and supporting said track, and means for locking said rests in adjusted positions.

3. A wood heel turning machine comprising a frame, a pair of lower brackets slidably mounted thereon, curved arms extending from the brackets, a lower track having its ends pivoted to said brackets, plugs slidably mounted vertically in the ends of said arms, stems mounted rotatably in said plugs, cylindrical rests carried by said stems and supporting the lower edge of said lower track, and nuts threaded on the lower ends of said plugs and adapted to engage the lower ends of said arms.

4. A wood heel turning machine comprising

ing a frame, a pair of brackets slidably mounted thereon, a rack carried by each bracket, pinions journaled in the frame and meshing with the racks, and worms journaled on the frame and meshing with the pinions, a track pivoted between said brackets, a pair of lower brackets slidably mounted on said frame having curved arms, a curved lower track having its ends pivoted to said brackets, and cylindrical rests eccentrically journaled in the free ends of said arms and supporting said track.

5. A wood heel turning machine comprising a frame, a pair of brackets slidably mounted thereon, a rack carried by each bracket, pinions journaled in the frame and meshing with the racks, and worms journaled on the frame and meshing with the pinions, a track pivoted between said brackets, a pair of lower brackets slidably mounted on said frame having curved arms, a curved lower track having its ends pivoted to said brackets, cylindrical rests eccentrically journaled in the free ends of said arms and supporting said track, and means for locking said rests in adjusted positions.

6. A wood heel turning machine comprising a frame, a pair of brackets slidably mounted thereon, a rack carried by each bracket, pinions journaled in the frame and meshing with the racks, and worms journaled on the frame and meshing with the pinions, a track pivoted between said brackets, a pair of lower brackets slidably mounted on said frame having curved arms, a curved lower track having its ends pivoted to said brackets, plugs slideable vertically in the ends of said arms, stems mounted rotatably in said plugs, cylindrical rests carried by said stems and supporting the lower edge of said lower track, and nuts threaded on the lower ends of said plugs and adapted to engage the lower ends of said arms.

7. A wood heel turning machine comprising a frame, a motor and a gear box supported by said frame, a drive shaft in said gear box and connected to said motor, an intermediate shaft journaled in said gear box adjacent the drive shaft, interengaging gears secured to said shafts, smaller gears carried by said shafts, cutter shafts journaled adjacent said drive and intermediate shafts, a pinion at the lower end of each cutter shaft and meshing with the adjacent smaller gear, and cutter blades at the upper end of each cutter shaft.

8. A wood heel turning machine comprising a frame, a motor and a gear box supported by said frame, a drive shaft in said gear box and connected to said motor, an intermediate shaft journaled in said gear box adjacent the drive shaft, interengaging gears secured to said shafts, smaller gears of condensite celoron carried by said shafts, cutter shafts journaled adjacent said drive and in-

termediate shafts, a pinion at the lower end of each cutter shaft and meshing with the adjacent smaller gear, and cutter blades at the upper end of each cutter shaft.

9. In a wood heel turning machine, a frame, cutter shafts journaled therein, means for driving said cutter shafts, a nut at the upper end of each shaft for holding a cutter thereon, the upper extremity of each shaft being squared, and means on the frame for confining against rotation a strap adapted for attachment to said nut whereby said shaft may be turned from the square end.

10. In a wood heel turning machine, a frame, cutter shafts journaled therein, means for driving said cutter shafts, a nut at the upper end of each shaft for holding a cutter thereon, the upper extremity of each shaft being squared, a rest formed adjacent each shaft, and having lugs arranged to confine the end of a strap having at one end a hole adapted to receive said nut, and at the other end sockets formed to cooperate with said lugs whereby said nut may be held fixedly with reference to the rest.

11. In a wood heel turning machine, a frame, cutter shafts journaled therein, means for driving said cutter shafts, and a nut at the upper end of each shaft for holding a cutter thereon, the upper extremity of each shaft being squared beyond the nut, whereby said nut may be removed from the shaft without twisting the main body thereof.

12. A wood heel turning machine comprising a frame, a motor and a gear box supported by said frame, a drive shaft in said gear box and connected to said motor, two smaller gears carried by said shafts, cutter shafts journaled in said gear box, cutter blades at the upper end of each cutter shaft, and a geared connection between said drive shaft and the cutter shafts whereby the cutter shafts are driven at equal velocities in opposite directions.

13. In a wood heel turning machine, a frame, cutter shafts journaled therein, means for driving the shafts, and a nut at one end of each shaft for clamping cutter blades thereon, each shaft having a portion, at the end which carries the nut, arranged for co-operation with a wrench, whereby the nut can be operated without twisting the main body of the shaft.

In witness whereof I have hereunto set my hand.

RALPH LESLIE RAYMOND.

CERTIFICATE OF CORRECTION.

Patent No. 1,748,994.

Granted March 4, 1930, to

RALPH LESLIE RAYMOND.

It is hereby certified that error appears in the printed specification of the above numbered patent requiring correction as follows: Page 2, line 42, for "Serial No. 158,100" read 158,000; page 4, lines 102 and 103, claim 12, strike out the words and comma "smaller gears carried by said shafts, "; and that the said Letters Patent should be read with these corrections therein that the same may conform to the record of the case in the Patent Office.

Signed and sealed this 9th day of December, A. D. 1930.

(Seal)

**M. J. Moore,
Acting Commissioner of Patents.**
